UNITED STATES PATENT OFFICE.

HENRY HOLMES, OF BROOKLYN, NEW YORK, ASSIGNOR OF THREE-FOURTHS TO
JOSEPH F. MCPHEE, OF NEW YORK, N. Y.

POWER-DRIVEN SAW.

1,411,967.

Specification of Letters Patent.

Patented Apr. 4, 1922.

Application filed June 7, 1919, Serial No. 302,380. Renewed February 21, 1922. Serial No. 538,368.

To all whom it may concern:

Be it known that I, HENRY HOLMES, a citizen of the United States, and a resident of the city of New York, borough of Brooklyn, 5 in the county of Kings and State of New York, have invented a new and Improved Power-Driven Saw, of which the following is a full, clear, and exact description.

This invention relates to a tree-felling saw, and aims to provide a device of this nature which shall not only be capable of felling a tree, but also, after the tree is lying upon the ground, the device may be utilized to saw the trunk into sections.

15 It is a well-known fact that innumerable mechanical saws have been designed, which are power driven, for the purpose of supplanting the lumber jack. It is known that these devices, almost without fail, have 20 proved impractical, for the reason that they, for the most part, include some special form of blade which cannot be adapted to the heavy usage under which, almost exclusively, the cross-cut saw stands up.

25 Further, devices have been designed which utilize a saw somewhat similar to the cross-cut saw, but these devices are incapable, without a great deal of adjustment, if at all, of sawing both horizontally, for the purpose 30 of felling a tree, and vertically, for cutting the same up into sections.

Saws have also been designed, none of 35 which have stood up under practical working conditions, by reason of the severe usage 40 which is given them in lumber camps. As these latter saws usually incorporated a rather delicate and extremely flexible saw passing over pulleys, which were very finely 45 adjusted as to tension, etc., the truth of the above assertion will readily be appreciated.

Having these defects in mind, I have designed a power-driven saw which will be capable of efficiently supplanting the labor of numerous pairs of lumber jacks, and in 45 which a conventional, or often larger than conventional, cross-cut saw blade is used.

I further construct a saw and its associated parts capable of being power driven, which shall be extremely rugged and simple 50 in construction, so that the same will stand up under the hardest kind of usage and exposure to the elements and which shall be adaptable to either horizontal or vertical sawing, thus performing any operation 55 which a pair of lumber jacks are capable

of doing, only, as aforesaid, performing these operations far faster and more efficiently than the lumber jacks, as well as working any length of time desired.

Reference is had to the accompanying 60 drawings in which like characters designate similar parts in all the views, and in which—

Figure 1 is an elevational view with the saws in a position for cutting the trunk of a tree into sections;

Fig. 2 is an elevational view with one of the saws in position for felling a tree;

Fig. 3 illustrates the power-driving connection utilized when the saw is in position illustrated in Fig. 2;

Fig. 4 is an enlarged view of a connection detail;

Fig. 5 is an enlarged detail view of the double bracket clamp adapted to retain the saw-supporting frame, which is used when 75 the tree is being felled, in applied position;

Fig. 6 illustrates the form of link by means of which the saw is suspended; and

Fig. 7 is an enlarged detail view of the connection, preferably provided between the 80 ends of the cross-cut saw and its supporting frame.

In these views the reference numeral 1 indicates a wheeled carriage, which is adapted to support a frame, comprising 85 crosspieces 2 upon which is arranged any suitable form of cradle 3 adapted to receive an engine, such as 4, which may be provided with reduction gears, etc. Extending upwardly from the crosspieces 2 are uprights, 90 such as 5, whose upper ends support a pair of horizontally-extending rods, such as 6, which may be braced, as indicated by the reference numeral 7.

A shaft 8, driven by the reduction gear- 95 ing, is provided on both of its ends, with crank arms, such as 9, which may be counterbalanced, as indicated by the reference numeral 10, if it is so desired. Pivotedly connected to the outer ends of each of the 100 crank arms 9 is a bar, such as 12. The bar 12 is preferably provided at its outer end with a pair of plates 13 secured on opposite faces of the bar 12; and mounted between the ends of the plates 13 is a block, such as 14, to which may be pivotally secured the inner end of a driving rod 15 by means of 105 a pair of plates, such as 16, extending upon opposite sides of the rod 15 and having their outer ends connected to the block 14 by 110

means of a pin passing therethrough. The plates 16 are formed with aligning openings, such as 17, through which pass a pin adapted to connect thereto a rod 18 which 5 may, when the saw is in the position illustrated in Fig. 1, swingingly support the bar 12 and the rod 15.

A cross-cut saw blade, such as 19, has secured to its outer ends a frame 20, which 10 may be connected adjacent one of its ends to the outer end of the rod 15 by any suitable means, such as a conventional clamping arrangement 21. One of the ends of the cross-cut saw blade 19 is preferably provided 15 with a grooved frame-engaging member 22, which is formed with an integral, or fixedly secured, screw-threaded rod 23 on which is mounted a hand-actuated nut 24.

Clamped around two parts of the frame 20 on opposite sides of the central point of the same, there is positioned a bracket, such as 25, which has extending between its end portions a guide 26. Mounted upon each of the guides 26 is a link 27 which is connected to one end of a helical spring, such 25 as 28, and which has its opposite end secured to links 29 which form the lower corners of a triangle, preferably constructed of chain, the upper sides of which are connected together by means of a link, such as 30. Mounted upon the outer ends of the horizontally-extending rods 6 are pulleys over which pass ropes, or chains, 31 having their outer ends connected to the link 30, whereby 35 when the inner ends of such ropes, or chains, 31 are moved, the saws will be caused, when the device is in the position illustrated in Fig. 1, to move in a vertical plane. It is to be understood that the ends of the ropes, or 40 chains, 31 may be controlled by means of a windlass or any other suitable arrangement, as desired.

It will now be seen that when the saw is mounted in the manner aforescribed, the 45 same will be adaptable for use in cutting up the trunks of trees into sections; and it is to be appreciated that while I have illustrated two cross-cut saw blades in applied position, I might readily utilize only one, or, 50 on the other hand, it would be permissible for me to duplicate the framework described continuously so that an entire tree trunk might be cut up into sections in one operation. However, for all practical purposes, 55 it will be found that two cross-cut blades will meet with all requirements, as two sections of the trunk will be severed from the body thereof simultaneously, and a machine of this size will prove less cumbersome than 60 would be the case if a greater number of blades were included in one machine.

It is to be appreciated that almost any suitable construction may be utilized by me to produce a reciprocation of the saw blades 65 without in the least departing from the

scope of my invention, and that numerous modifications of structure might be resorted to without affecting my basic principle.

It will be seen, when the blades 19 are reciprocated, that by virtue of the semiresilient 70 rocking suspension which is afforded by means of the springs 28 and associated parts, the blades function exactly in the same manner as when operated by hand, with the exception that the reciprocation is usually 75 faster and continuous. By virtue of this connection, it will be seen that the blade is always held properly vertically, that all the blades are reciprocated by mechanical means, that the teeth of the blades never 80 come out of contact with the cut being made, and that the weight of such blades and manner of stroke will be such that the teeth of the blades will cut equally well through green or dry wood. And by virtue 85 of the aforementioned suspension method of the saws, the operation of the same will be more efficient than if they were operated by hand.

Referring now more particularly to the 90 arrangement utilized in connection with the felling of trees where the blade works in a horizontal plane, it will be seen that the wheeled carriage is formed with a swivel bracket 32. To this swivel bracket there is 95 secured a rod 33 to which are clamped, by means of a double-bracket clamp 34, such as illustrated in Fig. 5, crosspieces 35 at right angles to the rod 33. These crosspieces have their outer ends provided, preferably, with spikes, as indicated by the reference numeral 36, which serve to firmly secure the crosspieces 35, rod 33, and wheeled carriage 1 in fixed relationship to the tree to be felled. The rear ends of the crosspieces 100 35 may be formed with legs, such as 37, serving to at all times keep the crosspieces spaced from the ground and the cross-cut saw positioned just above such crosspieces, well above the roots of the tree, or other obstruction therearound.

The cross-cut saw is moved from its suspended position below the rod 6, and its frame is laid upon the crosspieces 35. The outer ends of such frame, to which the cross-cut saw blade is secured, are slidably positioned upon the rod 33 to which is secured, at a point approximately intermediate the crosspieces 35, a pulley 38 around which the rope, or chain, 31 is passed. A second rope, 115 or chain, is affixed to the frame at a point approximately intermediate the brackets thereof, as indicated by the reference numeral 31', and both of such ropes, or chains, pass around pulleys, as indicated by the reference numeral 39, which pulleys are mounted on the rear end of a brace rod 40.

It is to be appreciated that the reciprocating driving rod 15, as well as the bar 12, might utilize an additional brace rod, and 130

for this reason I have provided a rod 41, whose inner end is pivotally secured at a point intermediate the bar and driving rod by means of a pin passing through the openings 17 formed through the plate 16, as indicated in Figs. 2 and 3. The opposite end of the rod 41 is pivotally secured, as indicated by the reference numeral 42, to any suitable part of the carriage frame.

10 In operation it will now be seen that the cross-cut saw blade 19 will be reciprocated by means of the bar 12 and its associated driving rod 15, but by virtue of the fact that the blade is now working in a horizontal plane, instead of a vertical plane, the saw will refuse to feed itself through the cut made in the tree; but it will be noted that the saw may be fed through the trunk of the tree by means of the ropes, or chains, 31 and 20 31', or, if it is desired, be retracted from a cut at will.

It is further to be understood that I may vary the construction and arrangement of parts in connection with the arrangement of the saw for felling trees without in the least departing from the scope of my invention.

Having thus described my invention, I desire to claim:

1. A power driven saw including a saw blade, a frame having its ends secured to

such saw blade, a pair of springs having their lower ends secured to such frame, their upper ends being connected together, means for lowering and raising such upper ends, and means for reciprocating such saw blade. 35

2. A power-driven machine including a saw blade, a frame having its ends secured to such saw blade, means for reciprocating such frame, a pair of springs having their upper ends secured together, and guides secured to such frame having the lower ends of such springs secured thereto, whereby the springs may be swung around such frame. 40

3. A power-driven machine including a saw blade, a frame having its ends secured to such saw blade, means for reciprocating such frame, a pair of springs having their upper ends secured together, guides secured to such frame and having the lower ends of such springs secured thereto, whereby the 50 springs may be swung around such frame, a flexible connector running from the junction of the springs and inter-changeable means arrangeable spaced from said springs, on the same side of the saw frame as the 55 saw or on the opposite side to which the connector runs to inter-changeably yieldingly draw the saw forward by the springs or to yieldingly support the saw frame thereby.

HENRY HOLMES.
